COTTON PICKER COMPRESSOR ASSEMBLY
 Mack A. West, P.O. Box 101, Paragould, Ark. 72450
 Filed July 14, 1966, Ser. No. 565,167
 6 Claims. (Cl. 56—44)

The present invention relates in general to harvesters, and in particular to cotton pickers. It is an improvement in pickers of the type disclosed in U.S. Patent 3,169,359, assigned to International Harvester Company.

Cotton pickers of this general type are equipped with compressor sheets which guide the plants laterally into engagement with banks of rotary spindles which engage and pull the cotton from the open bolls. In general, the compressor sheets are spring loaded or disposed so that they have vertical face contact with the plant foliage in planes that are parallel to the vertical axes of the drums which carry the sets of spindles.

When cotton matures the bolls open first from the ground to about half way up the plant stalk. If this open cotton is to be picked before the upper bolls open, it is usual practice to adjust the compressor sheets so that they bear tightly against the plant foliage and force the open bolls against the spindles. This action, of course, because of inflexibility of the compressor sheets, correspondingly tightens the upper portions of the sheets against the upper portions of the plants. The result is that many unopened bolls are pulled away from the upper portions of the plants and are lost, thus lowering the ultimate yield of the crop. If the compressor sheets are adjusted so that they bear only lightly on the upper portions of the plants to avoid stripping unopen bolls, then the lighter pressure of the sheets against the lower portions of the plants results in less picking of the open bolls, dropping cotton, and stringing it out on the stalks, again lowering the yield.

An object of my invention is to provide a compressor assembly having adjustable presser means operative independently of the compressor sheet, whereby to enable selective pressures to be applied to the plant foliage at various points in the vertical sets of picker spindles.

Another object is to provide a novel compressor assembly wherein spring loaded discs, corresponding in number and height to a stack of picker spindle sets with which they are associated, are individually adjustable to selected portions laterally advanced from the plant engageable face of their associated compressor sheet.

Still another object is to provide a compressor assembly in which selectively adjustable presser discs, corresponding in number and height to a vertical stack of sets of picker spindles with which they are associated, are self-conforming to the shape of plants they engage.

Other and incidental objects are apparent from the following detailed description in conjunction with the accompanying drawings, in which:

FIG. 1 is substantially a fragmentary sectional view taken horizontally through the forepart of a cotton picker similar to the picker shown in the aforesaid Patent 3,169,359, as equipped with my invention.

FIG. 2 is an elevation, partly broken away, taken substantially on line 2—2 of FIG. 1.

FIG. 3 is a sectional view taken substantially on line 3—3 of FIG. 1.

The known cotton picker to which my invention is applied has a pair of left and right counterpart portions 3 and 4 which respectively enclose vertical rotary picker drums 5 and 6, doffing mechanism 7 and spindle moistener mechanism 8. The drums mount stacks of vertically spaced picker spindles 9. These rotate about their individual, substantially horizontal axes to wind the cotton and pluck it from the bolls as the machine advances along a row of cotton plants.

The present invention concerns the means which presses the open cotton bolls into engagement with the spindles. It comprises an improvement upon the compressor sheet assemblies of the prior art. As here shown, the compressor sheet 10 consists of a leading front portion 11 and a rear portion 12. The front portion 11 is of substantially the height of the opposite spindle drum 5 and, with respect to the line of advance, diverges forwardly and outwardly. The forward end of the front portion 11 is curved around a vertical pivot post 13 which is fastened to the associated framework 14 of housing portion 4. The rear portion 12 diverges slightly rearwardly and outwardly relative to the line of advance and is located in the picking zone of the forward drum bank 5. In this area the picker spindles 9 project farther into the plant foliage and penetrate the plant for the full extent of their lengths, with their tips riding in an arcuate pocket 15 in the rear sheet portion 12 substantially concentric with the path of movement of the tips of the spindles.

20 The compressor sheet 10 is biased in the direction of the plant passage by torsion spring means which is anchored at 13a to the framework 14 of the machine portion 4. The spring has an output arm 16 which bears against the back face of the front portion 11 of the compressor sheets and biases it laterally toward the spindles 9 of the drum 5.

25 The improvement comprising my invention consists mainly in the provision of a stack of horizontal presser discs 17 that are independent of the compressor sheet, 30 and which are individually and separately movable to selective positions of adjustment relative to an adjacent set of picker spindles, whereby to force cotton bolls into engagement with the spindles at selected heights of the plant stalk. The discs are disposed inwardly behind the 35 pocket 15 in the rear portion 12 of the compressor plate. A vertical series of horizontal slots 18 is provided in the pocket 15. These slots and also the discs correspond in number to the number of spindle sets on the adjacent drum, and are arranged so that the horizontal planes in 40 which they lie pass midway between adjacent upper and lower spindles as shown in the broken away area of FIG. 2.

45 Each disc 17 is horizontally aligned with a corresponding slot 18 through which a portion of the disc normally extends in slidable relation. Support for each disc is provided by a pair of vertically spaced parallel arms 19 that are pivoted at their forward ends on a vertical hinge post 20 mounted in the front portion 11 of the compressor sheet between its inwardly directed top and bottom edge flanges 21 and 22, respectively. The rear ends of each 50 unit pair of the disc support arms 19 mount between them a vertical axle 23 on which the corresponding disc is freely rotatable between the end portions of the arms.

55 Each disc axle has pivotal connection with the ends of a yoke 24 that constitutes part of an adjustment rod 25. This rod extends horizontally within the casing that houses the compressor disc assembly and is slidably axially through the exterior wall 26 of the casing. The outer end of the rod projects outwardly beyond the casing wall and is threaded to receive an adjusting nut 27. At the 60 inner side of the casing wall the rod is surrounded by the coils of an expansion spring 28 which bears at one end against the casing wall and at its other end against a collar 29 that is slidable on the rod to vary the tension of the spring. The collar is anchored in various positions of adjustment by a set screw 30.

65 An important feature of my invention is the location of the hinge post 20 close to the pivot 13 at the front end of the compressor sheet. This arrangement insures that the presser discs will not be affected by movements 70 of the compressor sheets. Consequently, the compressor sheets can be adjusted to positions in which they func-

tion merely as guides for the plants, exerting practically no pressure that would force the bolls against the picker spindles; the imposition of which pressure is a function of the individual discs 17. In effect, my invention transforms the uniform bottom to top pressure exerted by rigid compressor sheets into a flexible, selectively variable pressure exerted by the individually adjustable spring biased discs.

It is to be understood that the compressor sheet assembly for the left portion 3 is identical to the above described assembly for the right portion 2, except that the hinge post for the arms which carry the discs will be mounted on the rear portion of the compressor sheet.

Operation

As the compressor assemblies for portions 3 and 4 are the same, the following description in regard to the assembly in the right portion 4 will suffice for both. The compressor sheet 10 is initially adjusted to a position in which it bears only lightly against the foliage of the plants it guides into the path of the picker spindles 9 of the left portion 3. With the compressor sheet in this position its pressure is not sufficient to effect maximum picking, as hereinbefore stated. The presser discs 17 are then adjusted individually by manipulation of the nuts 27 to project the discs through the slots 18 so that portions of the discs will extend laterally from the compressor sheet in position to pass between upper and lower adjacent spindles as shown in FIG. 2, and to a degree of penetration determined by the setting of the nuts. As there is a disc for each horizontal set of spindles, and because each disc can be adjusted individually to apply more or less pressure as needed at selected heights of the plant stalks, it is an easy matter to adjust the discs to apply at any height of a plant the pressure best suited to effect at that height a maximum picking from the bolls which are open at the time a crop is harvested. This is accomplished by appropriate adjustment in the tension of the various springs.

It is to be understood that the herein disclosed embodiment of my invention is illustrative of a practical example and that the invention is not restricted thereto. It may comprise any structure falling within the scope of the invention as claimed.

I claim:

1. In a cotton picker machine having vertical rotary drums carrying horizontal sets of picker spindles, and a spring biased compressor sheet for guiding plants into engagement with the spindles; presser means associated with the sheet and operative independently thereof to pass horizontally between adjacent sets of the spindles and force the plant foliage into engagement with the spindles; said sheet having apertures for passage therethrough of said presser means.
2. In the structure of claim 1, said presser means comprising a plurality of freely rotatable horizontal discs corresponding in number to the spindle sets; and separate spring means for each disc biasing the disc to project laterally through an adjacent sheet aperture into yieldable engagement with the plant foliage.
3. In the structure of claim 2, the sheet aperture being a horizontal slot in the compressor sheet.
4. In the structure of claim 3, means for adjustably varying the tension of the spring means for each presser disc independently of all the others.
5. In a cotton picker machine having vertical rotary drums carrying vertically spaced sets of horizontal picker spindles; a series of vertically spaced and freely rotatable presser discs arranged horizontally in planes such that each disc is adapted to pass horizontally between the upper and lower sets of spindles adjacent thereto; an individual horizontal adjustment rod carrying each disc and slidable axially through a fixed element of the machine; and means for retaining said rod in various positions of penetration between its adjacent sets of upper and lower spindles.
6. In the structure of claim 5, spring means individual to each rod and yieldably biasing its disc to the farthest penetration between adjacent spindles permitted by the rod retaining means.
